UNITED STATES PATENT OFFICE.

EDWARD CRAIG, OF ST. JOSEPH, MICHIGAN.

MACHINERY AND METHOD FOR MAKING RECEPTACLES.

Application filed July 18, 1921. Serial No. 485,736.

To all whom it may concern:

Be it known that I, EDWARD CRAIG, a citizen of the United States, and a resident of St. Joseph, county of Berrien, State of Michigan, have invented a certain new and useful Improvement in Machinery and Methods for Making Receptacles, of which the following is a specification.

This invention relates to machinery for making ice cream pails, or similar receptacles, and is in the nature of an improvement on the construction and mode of operation shown and described in the co-pending application Serial Number 485,128, filed 10 15th day of July, 1921. (Patent granted September 23, 1924.) In said prior application, as in this application, the blanks are formed obliquely to the sheet or long strip of paper from which the blanks are cut by 15 the blanking machine, before the blanks are fed to the forming machine by which each blank is folded to form a pail or other receptacle. Also, as in said prior application, the present invention involves the presentation of each blank to the forming means 20 in such a manner that the blank stands squarely in the forming machine, instead of obliquely or at an angle as it does in the blanking machine, whereby waste is minimized or considerably reduced, without reducing the size of the pails or other receptacles. In said prior co-pending application this is accomplished by turning the forming machine partially around, so that it stands 25 at an angle to the direction of travel of the long sheet or strip of paper from which the blanks are made, whereby the longitudinal center line of the machine is disposed at an angle to the longitudinal center line of the 30 blanking press, or to the direction of travel of the sheet from the printing press to the blanking press and from the latter to the forming machine. In other words, the blanks are formed at an angle to the length 35 of the sheet or strip of paper, and the forming machine is disposed at the same angle, whereby when the finished blank at the end of the sheet reaches the forming machine, the blank is in correct position for the folding 40 thereof. In accordance with the present invention, however, the said forming machine stands squarely in line with the blanking press and the printing press, so that the longitudinal center line of each ma-

chine is the same as that of the others. 55 However, in order to present the blanks properly to the forming means, after being thus formed obliquely to the length of the sheet in the blanking press, the forming machine is provided with means for automatically turning each blank partially around in the forming machine, so that it will stand squarely in folding position relatively to the folding means. In other words, in each case the blank has one position in the blanking press, and a different position in the forming machine, relatively to each machine, but in said prior application this is accomplished by turning or skewing the forming machine partially around, while in this application, as will hereinafter more fully appear, the desired result is accomplished by turning the blank itself partially around at about the time that it arrives in position to be folded. In either case, however, the 65 desired saving of materials is accomplished, as the sheet or strip of paper, for any given size of pail, is somewhat narrower than would be the case were the blanks formed 70 squarely thereon, or with the rectangular bottom section of each blank in position with two of its edges parallel with the length of the sheet and the other two edges at right angles thereto, for in such case the sheet would have to be much wider in order 75 to provide sufficient material for certain flaps with which each blank is desirably provided in order to produce a pail or receptacle of desired character. According to 80 the present invention, the printing press feeds the sheet of paper to the blanking press, and from the latter the connected blanks are caused to feed forward to the forming machine. This is advantageous, of course, as fully set forth in said other application, and in addition the cutting of the 85 blanks in the manner described tends to minimize waste, and while this is accomplished in one way in said prior application, the same thing is accomplished in a 90 specifically different way in this application, but broadly in the same way, as will hereinafter more fully appear.

To these and other useful ends the invention consists in matters hereinafter set 95 forth and shown in the accompanying drawings in which:

Figure 1 is a side elevation of a machine

for making ice cream pails, embodying the principles of the invention.

Figure 2 is a plan of said machine.

Figure 3 is an enlarged plan of certain portions of said machine, illustrating more particularly the method of forming the blanks and of delivering the same successively to the forming means of the machine by which the blanks are folded and provided with bail shaped wire handles.

Figure 4 is a detail fragmentary sectional view showing the device for partially turning each blank around at about the time that it arrives in the desired position for the folding thereof by said forming means.

Figure 5 is an enlarged vertical section on line 5—5 in Figure 1.

Figure 6 is a perspective of the finished pail.

Figure 7 is an enlarged plan of one of the blanks shown in Figure 3.

As thus illustrated, the invention comprises a suitable base 1 upon which are mounted in suitable manner the printing press 2, the blanking press 3 and the forming machine 4 by which the blanks are folded and equipped with the bail shaped wire handles. As explained in said prior application, the printing press has rolls 5 for receiving the paper between them, the upper roll having impression means 6 thereon disposed obliquely or at an angle thereto. The paper is fed from roll 7 as usual, to said printing press, and is fed by feed rolls 8 to the blanking press 3, the latter being adapted to form the blanks obliquely or at an angle to the length of the sheet 9 of paper. For this purpose, of course, the upper and lower dies 10 and 11 of the blanking press are suitably constructed and provided with means for cutting and creasing and scoring the paper to produce the foldable blank shown in Figure 3, and shown on a larger scale in Figure 7, it being observed that the rectangular bottom section 12 of each blank does not stand squarely on the long sheet or strip of paper, but is twisted or skewed partly around until it stands at an angle to said sheet or strip of paper. In this way the blanks formed by the blanking press are connected together at their front and rear edges 13 and 14, while the side edges 15 of the blanks are formed by the two side edges of the long sheet or strip of paper, it being observed that each blank is practically square or rectangular in form, the flaps for the cover of the pail being formed at the four corners of each blank. Were the blanks formed squarely or at right angles to or parallel with the length of the sheet, which position is indicated in dotted lines at 16 in Figure 3, it will be seen that these flaps of the blank would necessitate the provision of a much wider sheet or strip

of paper. Therefore, by skewing the blanks around at an angle of substantially 45 degrees, as shown, the sheet or strip of paper can be considerably narrower for any given size of blank or pail, and in addition the large three-cornered sections which would be cut from between the blanks, if they were formed corner to corner instead of edge to edge, are avoided and do not occur, thus tending to minimize waste in cutting and forming the blanks. Obviously, however, in a forming machine of any suitable or desired character, the blank must stand squarely in folding position, relatively to the forming means, as indicated in dotted lines at 16, in Figure 3, and hence the necessity for causing each blank to have a position in the forming machine which is different from the position which is occupies in the blanking press. In the present case, as shown more clearly in Figures 3 and 4, this is accomplished by partially turning the blank itself around into the desired position, whereby the forming machine 4 may stand squarely in line with the other two machines. For this purpose a lever 17 is pivoted on the forming machine at 18 and is connected by a link 19 with the lever 20 which carries some sort of means 21 for engaging the cam groove 22 of the rotary cam 23 on the transverse shaft 24 of said machine. The upper end of the lever 17 works in a slot 25 in the top or table of the forming machine. At the proper time, it will be seen, the upper end portion of the lever 17 engages the blank to turn the latter partially around in the manner shown and described. Of course, before this can be done, the blank must be cut off or severed from the long sheet or strip of paper, and this is done in the present case by means of a knife or cutting device 26 which is pivoted at 27 on the forming machine, and which is operated in any suitable or desired manner to cut the paper along the lines 13 and 14 to sever the blanks successively from the long sheet or strip of paper. It will be understood that the various operating parts are so timed or governed in their action that the knife or cutting device 26 cuts off the blank at the proper time, and so that the lever 17 then skews or turns the blank partially around until it occupies the desired position in the forming machine. Of course, the long sheet or strip of paper is fed intermittently in the blanking press, so that it stands still while being blanked in the blanking press 3, and while this press is forming the blank, the forming machine 4 is folding another blank and applying the wire handle thereto. At such time there are two complete blanks between the one which is being formed and the one which is being folded, as will be seen from an inspection of Figure 3 of the

drawings. The printing press may feed the paper continuously, as is common, or in any suitable manner. Hence the feeding means are so timed that the sheet or strip of paper is caused to move in the desired manner, through the blanking press from the printing press to the forming machine, thus gradually converting the sheet or strip of paper into pails or other receptacles of any desired form or character. To assist in the adjustment of the blank in the position indicated by dotted lines 16 in Figure 3 a stationary stop or engaging device 28 is provided on the table of the forming machine, to engage one forward corner of the blank, so that by the proper operation of the lever 17 the blank is twisted or skewed around until it occupies the position necessary for the folding thereof.

It will be understood that the printing press or blanking press can be of any suitable or known character, such as those referred to in said prior application, the exact construction being unimportant, except that the printing means and the blanking means must be disposed in position to form the blanks obliquely or at an angle on the sheet or long strip of paper, in order to economize in the use of materials. The forming machine may be of any suitable character, such as the one referred to in said prior application, the exact construction being unimportant, and the only requirement being that some means be provided, in this particular case, in order to accomplish the purpose of the improvement, for skewing or turning the blank partially around into the position which it must occupy in the forming machine, as distinguished from the position which it occupies with good results in the blanking press. Like the blanks and pails shown in said prior application, the method and machinery involved in this case produce blanks and pails having two-ply overlapping flaps or double thickness portions 29 and 30 at opposite sides of each pail. This is done with the blanking press, of course, this machine being adapted to blank out portions of the paper or other sheet material in such a manner that each blank, when folded in the manner shown and described, has the two overlapping flaps 29 and 30 at the opposite sides of the pail on the outer sides thereof disposed in such position that the externally arranged two-ply flaps are then fastened together in the forming machine by the insertion of fastening means in the desired manner. Any suitable fastening means can be employed, of course, but in the present case the receptacle shown and described is a pail and, as such, it desirably has a bail shaped wire handle 31, the ends of which are inserted in position to form said fastening means. In other words

the opposite ends of the handle are inserted through five thicknesses of sheet material at each side of the pail, the forming machine being adapted to not only fold the blanks in this manner, but also to bend and 70 insert the handles 31 in the desired manner.

Thus when the blank is made its bottom 12 is at an angle of forty-five degrees to the length of the strip, but when skewed into folding position said bottom is at right 75 angles to said strip. In this way the blank is only skewed after being cut off, and is still in line centrally with the center line of travel of the strip. The pail machine 4 has its transverse dimension at right 80 angles to the straight line of travel from the blanking press, and the longitudinal dimension of all three machines is parallel with said line of travel.

With the construction and mode of operation so described, in the example or embodiment of the invention disclosed, it will be seen that no part of the sheet feeding means ever touches a severed blank, for the blank is not cut off until after the blank 90 ahead has been converted into a receptacle, and not until after the blank to be severed has been released from the sheet or strip feeding means. Necessarily, therefore, the method involves the conversion of each 95 blank into a pail or other receptacle before the next blank is cut off. Each severed blank, then, is skewed into position by the finger or lever 17, and is then converted into a receptacle by the upward stroke of 100 the plunger 32 shown in dotted lines in Fig. 1 of the drawings, it being understood that this plunger is adapted to co-operate with devices (not shown) of any suitable character to fold the different portions of the 105 blank preliminary to the insertion of the ends of the handle 31, thereby to produce the receptacle shown in Figure 6 of the drawings. The pail or receptacle forming machine is, therefore, of any suitable, known 110 or approved form, and of whatever form is disposed directly in line with the blanking press, and directly in line with the straight line of feed of the sheet or strip from which the blanks are made. Consequently, the forming machine, because of the skewing device, is permitted to stand transversely of the line of feed, so that its transverse dimension is at right angles to the line of feed of the strip or sheet of 115 paper, and whereby the transverse dimension of the forming machine is parallel with the transverse dimension of the blanking press, as well as parallel with the transverse dimension of the printing press. Necessarily, therefore, each blank is skewed or turned an eighth of a full rotation about a vertically disposed axis, and converted into 120 a pail, or other receptacle, before the next blank is cut off. The vertical axis about 125 130

which the severed blank is skewed is on the longitudinal center line of the sheet or strip of paper, so that the blank by its skewing motion is not displaced laterally, but is merely given an eighth of a complete rotation about its vertical axis and is moved forward a distance to bring it into the position necessary for the folding thereof and for the attachment to the handle of the receptacle. As stated, though, the skewing and conversion of the severed blank into a receptacle necessarily take place before another blank can be cut off, but in the meantime other blanks are in various stages or process of preparation.

Of course, with the construction and arrangement shown and described, the feeding motion of the sheet or strip is employed to feed the blanks into the forming machine. Each blank needs some skewing or readjustment after it is received into the forming machine, but nevertheless each blank arrives in the forming machine before it is cut off, and each blank is converted into a receptacle before the next blank is severed from the strip or sheet.

What I claim as my invention is:

1. The process of making receptacles, comprising the feeding of a long sheet or strip of paper, blanking out portions of said paper to form blanks for the making of the receptacles, cutting off the blanks successively, skewing or partially turning each cut off blank around into the position required for the folding thereof, by turning the blank one-eighth of a full rotation about a vertically disposed axis which is still in line with the center of the strip when the blank reaches the folding position, when viewed from above, so that prior to folding the blank has only this skewing motion after being cut off, and then folding the blank to produce the desired receptacle, whereby each severed blank is necessarily converted into a receptacle before another blank is severed from the strip.

2. The process specified in claim 1, in which the blanking is done in such a manner that the blanks are disposed obliquely or at forty-five degree angles to the length of the sheet or strip of paper, thereby necessitating said skewing or turning of the severed blank in order to place it at right angles to said strip and in correct position for the folding thereof.

3. The process specified in claim 1, comprising the insertion of a bail shaped wire handle in each receptacle.

4. The process specified in claim 1, comprising the printing of certain marks on the paper, before the latter arrives in position to be formed into blanks, so that the sheet or strip of paper thus both printed and blanked out in the desired manner is caused to feed toward the position for the folding

of the blanks, the printing being so positioned that said skewing or turning of the blanks is necessary in order to bring the printed portions thereof into position for the proper folding of each blank.

5. The process specified in claim 1, comprising the formation of two-ply flaps or overlapping portions of double thickness, so that one two-ply flap overlaps another two-ply flap at opposite sides of the receptacle, and inserting fastening means through the five thicknesses thus produced at each side of the receptacle.

6. The process specified in claim 1, comprising the formation of overlapping two-ply flaps at opposite sides of the receptacle, thus forming five thicknesses at each side of the receptacle, and the insertion at opposite ends of a wire handle through the five thicknesses at each side of the receptacle, thereby to hold the two-ply flaps in position externally of the receptacle.

7. In machinery for making receptacles, the combination of a blanking press, means for feeding a sheet or long strip of paper through said blanking press, whereby the blanking press is operative to form successive blanks on the sheet, a forming machine arranged to receive the blanks from the blanking press, by the feeding motion of the sheet or strip of paper, means for successively cutting off the blanks as they arrive still attached to the strip in the forming machine, means for automatically skewing or partially turning each severed blank around from its position on the strip and into the position necessary for the folding thereof, operative to stop the blank in position with its center still in line with the center of the strip, when viewed from above, and means to drive said machinery, whereby each severed blank is necessarily converted into a receptacle before another blank is severed from the strip.

8. A structure as specified in claim 7, said blanking press being operative to form the blanks obliquely or at an angle to the length of the sheet or strip of paper, and said forming machine being disposed squarely in line with the blanking press and the line of feeding motion of the long sheet or strip of paper, thereby requiring said skewing or turning of the severed blank in order to enable it to stand squarely in the forming machine, instead of obliquely as it stands in the blanking press.

9. A structure as specified in claim 7, in combination with means for printing certain marks on the paper, before the latter arrives in the blanking press, so that the paper thus both printed and blanked out is automatically passed through and from the blanking press to the forming machine.

10. A structure as specified in claim 7, said means for skewing or turning the blanks

into folding position comprising a stationary stop for engaging one portion of the blank and a movable element for engaging another portion thereof.

5 11. A structure as specified in claim 7, said feeding means comprising a printing press having a roll for placing certain marks on the sheet before the latter arrives in the blanking press, said printing press and
10 blanking press and forming machine being disposed all squarely in line with each other, so that each machine is parallel with the line of travel of said strip, and said blanking press being adapted to form the blanks
15 obliquely or at angles to the length of the sheet or strip of paper, so that said skewing or turning of each severed blank is necessary in order to enable the blank to stand squarely in the forming machine, instead
20 of obliquely as it stands in the blanking press.

12. In machinery of the class described, the combination of a blanking press, means for feeding a sheet or long strip of paper to and through and from said blanking press, so that certain portions of the paper are blanked out on the sheet, a forming machine to receive the blanks from the blanking press, and a device to automatically cut off the end blank, said forming machine standing squarely in line and parallel with and at right angles to the straight line of travel from blanking press, and the center of the blank in the forming machine being
35 in line with the center of the strip, when viewed from above, together with means to drive said machinery whereby each severed blank is necessarily converted into a receptacle before another blank is severed from the
40 strip.

13. A structure as specified in claim 12, in combination with means for severing the blanks from the sheet, as they arrive in the forming machine, and means for properly
45 positioning each severed blank in the forming machine.

14. A structure as specified in claim 12, in combination with means for automatically positioning each blank in the proper po-

sition for the folding thereof in said forming machine.

15. A structure as specified in claim 12, in combination with means for successively severing the blanks from the sheet or strip of paper as they arrive in the forming machine, and for automatically skewing or partially turning each severed blank around to bring it into a position in the forming machine which is different from the position which it occupies in the blanking press. 60

16. In machinery for making receptacles, the combination of a printing press for feeding a sheet or long strip of paper with the printing disposed obliquely thereon, a blanking press arranged to receive the 65 obliquely disposed printed portions of the paper, and adapted to convert said printed portions into obliquely disposed blanks, a receptacle forming machine arranged to receive the blanks from the blanking press, by 70 the feeding motion of the sheet or long strip of paper, said printing press and blanking press and forming machine all standing squarely in line with each other, and parallel with the path of feed, so that the trans- 75 verse dimension of each machine is at right angles to the line of travel of said strip, means to sever the blanks as they arrive in the forming machine, so that the delivery position of each blank in the forming ma- 80 chine is obliquely or at an angle to the length of the sheet or strip of paper, when viewed from above, which is the same as the position of the blank in the blanking press, and instrumentalities for thereafter skewing 85 or partially turning each severed blank around into the position necessary for the folding thereof, with the center of the skewed blank still in line with the center of the strip, when viewed from above, so 90 that each blank when folded stands squarely in the folding machine, instead of obliquely as it does in the blanking press, whereby each severed blank is necessarily converted 95 into a receptacle before another blank is severed from the strip.

EDWARD CRAIG.
